UNITED STATES PATENT OFFICE.

LEOPOLD KRAUS, OF BIRMINGHAM, CONNECTICUT.

DESIGN FOR THE ORNAMENTATION OF CORSETS.

SPECIFICATION forming part of Design No. 18,651, dated October 2, 1888.

Application filed July 6, 1888. Serial No. 279,925. Term of patent 14 years.

To all whom it may concern:

Be it known that I, LEOPOLD KRAUS, a citizen of the United States, and a resident of Birmingham, New Haven county, Connecticut, have invented certain new and original Improvements in Design for Corsets, of which the following is a specification.

The present design relates to the surface ornamentation of corsets; and it consists in a corset having a series of plain strips or sections and a series of ornamental strips or sections in relief upon the plain body of the corset.

Referring to the accompanying illustrations, in which Figure 1 is an elevation of a corset and Fig. 2 a sectional view thereof, the sections *b* are plain and the intermediate or ornamental sections, *a*, are of lace-like open-work pattern in relief upon the plain body of the corset.

The corset thus ornamented is rendered lighter in appearance, and an effect is produced that is highly ornamental.

What I claim is—

The design for the ornamentation of corsets, the same consisting of the plain sections *b* and the ornamental sections *a* of lace-like open-work pattern in relief on the plain body portion of the corset, substantially as herein shown and described.

In testimony whereof I have signed my name to this specification in the presence of two subscribing witnesses.

LEOPOLD KRAUS.
